UNITED STATES PATENT OFFICE.

MILTON L. DODGE, OF NEWBURYPORT, MASSACHUSETTS.

METHOD OF MAKING TURN-SHOES.

1,258,201.

Specification of Letters Patent. Patented Mar. 5, 1918.

Application filed June 9, 1917. Serial No. 173,745.

To all whom it may concern:

Be it known that I, MILTON L. DODGE, a citizen of the United States, residing at Newburyport, in the county of Essex and State of Massachusetts, have invented new and useful Improvements in Methods of Making Turn-Shoes, of which the following is a specification.

The object of the present invention is to provide an improved method of making turn shoes. In United States Letters Patent 1,221,153 granted me April 3, 1917, I have disclosed a method by which a stiff molded counter-stiffener may be used in the manufacture of turn shoes. According to the latter said method the counter-stiffener is arranged right side up on the sole of a shoe that is lasted wrong side out, and its position is fixed by driving fasteners through the forward ends of the heel-seat flange, in the forward ends of the heel-seat area. The shoe is afterward turned right side out, the rear portion of the counter-stiffener is anchored to the sole by driving the usual heel-seat nails through the sole, through the flange of the counter-stiffener, and through a nail-receiving member that is arranged inside the counter-stiffener. When these and other operations have been performed a heel is attached in the usual manner. The fasteners that are driven through the forward ends of the flange of the counter-stiffener to fix the position of the latter before the shoe is turned, as hereinbefore explained, are not driven all the way through the sole for the reason that it is not desirable to have them appear on the bottom of the sole. They are, therefore, turned back and clenched in the stitch-receiving channel of the sole. While this arrangement of the fasteners, and the method of clenching them, are satisfactory so far as results are concerned, the method requires more time than some shoe manufacturers are willing to allow for it. One object of the present invention is to save time in the step of fixing the position of the counter-stiffener, without having the undesirable result of having the fasteners appear on the bottom of the finished shoe. I accomplish this result by my present improved method, according to which the fasteners for fixing the position of the counter-stiffener, instead of being driven through the forward ends of the flange, are driven through the flange within the area of the heel-seat, so that al-

though they may be driven all the way through the sole they will be covered and concealed by the heel that is afterward attached to the shoe. 60

Another object of the invention is to save the time hitherto devoted to the so-called "heel-seat nailing" operation. To this end I use a counter-stiffener the heel-seat flange of which is wider than those usually employed, instead of driving the usual heel-seat nails to anchor the rear portion of the counter-stiffener to the sole I arrange the heel attaching nails so that they will pass through the flange of the counter-stiffener 70 and anchor the latter.

Referring to the accompanying drawings which form a part of this specification:

Figure 1 represents a top plan view of a lasted shoe, wrong side out, with a stiff 75 molded counter-stiffener arranged upon and anchored to the heel-seat portion of the sole by fasteners located within the heel-seat area.

Fig. 2 represents a cross-section on a 80 larger scale through the structure intersected by line 2-2 of Fig. 1, showing the tacks by which the counter-stiffener is fixed in the desired position relatively to the sole.

Fig. 3 represents a face view of a nail-receiving member that is used to provide a suitable bearing surface for the heel of the wearer, and that is long enough to stiffen the shank portion of the sole. 85

Fig. 4 represents a longitudinal section 90 through the heel portion of said shoe after the latter has been turned right side out, after the lining has been tucked into the counter-stiffener, and after the nail-receiving member has been fastened to the sole. 95

Fig. 5 represents a longitudinal section 100 similar to Fig. 4 excepting that the shoe is represented in a finished condition, the heel-attaching nails being arranged to anchor the rear portion of the counter-stiffener. 105

Fig. 6 represents a cross-section through the heel portion of the finished shoe, showing other heel-attaching nails extending through the flange of the counter-stiffener to anchor the latter.

The same reference characters indicate the same parts wherever they occur.

The sole and upper are indicated at 10 and 11 respectively. The forward portion and rear portion of the lining are indicated 110 at 12 and 13 respectively, these portions being defined one from another by transverse

slits 14, 14 arranged in a line substantially coincident with the forward ends of the counter-stiffener hereinafter described. The upper and the portion 12 of the lining are connected to the sole by the usual inseam stitches 15, and although the inseam extends around the heel portion of the shoe the heel portion 13 of the lining is left free, as shown by Figs. 1 and 2, until after the shoe is turned.

After the shoe has been lasted and sewn as shown by Fig. 1 a stiff molded counter-stiffener 16 is arranged right side up on the heel-seat portion of the sole. In the present instance the heel-seat flange 17 of the counter-stiffener is relatively wide, and the forward portions of said flange are lapped one over the other and connected directly to each other by a suitable fastener such as a staple 18. The ends of the staple are preferably clenched. The fastener 18 maintains the width of the counter-stiffener, independently of any fasteners that may be driven to anchor the stiffener, and if the correct width is determined when the fastener 18 is driven the shoe will fit snugly against the shank portion of the foot instead of spreading at this point.

Since the forward ends of the flange 17 are lapped their aggregate thickness might cause an undesirable lump on the sole, notwithstanding the fact that the edges of the flange are skived, and in order to graduate such thickness otherwise than by skiving, I arrange one of the front edges such as 19 ahead of the other such as 20.

When the counter-stiffener has been arranged as shown by Fig. 1 it is anchored to the sole by driving one or more metallic fasteners such as tacks 21, 21. These tacks are driven from the inside of the counter through the flange 17 and sole 10, within the heel-seat area, and if their shanks are long enough their points will be turned back and clenched on the bottom of the sole by the metal plate with which the last is shod (see Fig. 2). The counter-stiffener is thus anchored substantially between its extreme front and extreme rear, prior to turning the shoe right side out, and in consequence of locating the anchoring tacks 21 substantially midway between the ends of the stiffener the latter is given a more secure initial anchorage than it would have if the first anchoring fasteners were driven in the front end as shown in said Patent 1,221,153.

The function of the tacks 21 is to keep the counter-stiffener in the desired position until the latter is more securely anchored, as hereinafter explained, and when said tacks have been driven the last may be withdrawn from the shoe and the latter may be turned right side out. In the course of turning the shoe the heel portion 13 of the lining will be carried over the upper edge of the counter-

stiffener and will be tucked into the latter so that its marginal portion will lie upon the flange 17 as shown by Figs. 4, 5, and 6. A nail-receiving member 22 of suitable sheet material may then be arranged to lie partly 70 on the turned marginal portion of the lining within the counter-stiffener. A tack 23 may then be driven from the inside of the shoe through the member 22 and through the sole to fix the position of the member 75 22 so that the latter will remain in the desired position to receive the heel-attaching nails. It would be preferable to turn back and clench the point of the tack 23 as shown by Figs. 4 and 5.

The last may now be replaced in the shoe, and the position of the counter-stiffener will be maintained by the tacks 21, while that of the member 22 will be maintained by tack 23, during the leveling operation and any 85 other operation that may be performed prior to attaching the heel. If it is desired to use the member 22 to stiffen the shank portion of the shoe the shank portion of the member 22 may be attached to the sole by 90 glue 24 and by a tack 25, the latter being preferably too short to pass all the way through the sole. Nails 26 by which the heel 27 is attached are arranged to pass through the heel-seat flange 17 of the counter-stiffener as shown by Figs. 5 and 6, thus anchoring the counter-stiffener more securely around the heel-seat of the shoe, and dispensing with the necessity of driving the usual heel-seat nails for that purpose 100 alone. The utilization of the heel-attaching nails 26 for this additional purpose is made possible by making the flange 17 wide enough to insure anchorage. The points of the nails 26 are preferably driven through the member 22, and turned back and clenched. I have not attempted to represent the lifts of which the heel blank may be made, but the usual top lift is indicated.

I claim:

1. In the art of making turn shoes, the herein-described method which consists in arranging a stiff molded counter-stiffener right side up on the sole of a shoe that is lasted wrong side out, fixing the position of said counter-stiffener by driving fasteners through the heel-seat flange thereof and through the sole within the area of the heel-seat, turning the shoe right side out, and attaching a heel thereto in position to occupy said area.

2. In the art of making turn shoes, the herein-described method which consists in arranging a stiff molded counter-stiffener right side up on the heel-seat portion of the sole of a shoe that is lasted wrong side out, fixing the position of said counter-stiffener by driving one or more fasteners through the heel-seat flange thereof and into the sole, turning the shoe, arranging a nail-

receiving member upon the heel-seat flange of the counter-stiffener, fixing the position of said nail-receiving member, and anchoring the rear portion of the counter-stiffener 5 by attaching a heel with nails driven through the sole, through the rear portion of said flange, and through said nail-receiving member.

3. In the art of making turn shoes, the 10 herein-described method which consists in lapping the forward portions of the heel-seat flange of a counter-stiffener, fastening such lapped portions directly to each other, arranging such counter-stiffener right side 15 up on the sole of a shoe that is lasted wrong side out, fixing the position of said counter-stiffener by driving fasteners through the heel-seat flange thereof and through the sole at opposite sides of the longitudinal median 20 line, and approximately midway between the front and rear ends of the counter-stiffener, leaving the counter-stiffener otherwise free to creep relatively to the sole, turning the shoe right side out, and fixing the counter- 25 stiffener more securely to the sole by attaching a heel with nails arranged to extend through said flange.

4. In the art of making turn shoes the herein-described method which consists in at-

taching a stiff molded counter-stiffener right 30 side up on the sole of a shoe that is lasted wrong side out, turning the shoe right side out, and anchoring the counter-stiffener to the heel-seat portion of the sole by attaching a heel with nails arranged to extend through 35 the heel-seat flange of the counter-stiffener.

5. In the art of making turn shoes, the herein-described method which consists in arranging a stiff molded counter-stiffener right side up on the sole of a shoe that is 40 lasted wrong side out, fixing the position of said counter-stiffener by driving fasteners through the flange thereof and through the sole at opposite sides of the longitudinal median line, leaving the front and rear portions of the counter-stiffener free to creep 45 relatively to the sole, turning the shoe right side out, arranging a nail-receiving member upon said flange, fixing the position of said nail-receiving member by driving a fastener 50 therethrough and into the sole, and anchoring said counter-stiffener and said nail-receiving member by attaching a heel with nails arranged to extend through said flange and through said member. 55

In testimony whereof I have affixed my signature.

MILTON L. DODGE.
